DESIGN FOR A SHOE SOLE

William F. Cairns, New Haven, Conn., assignor to
United States Rubber Company, New York,
N. Y., a corporation of New Jersey

Application January 14, 1939, Serial No. 82,362

Term of patent 7 years

To all whom it may concern:

Be it known that I, William F. Cairns, a citizen of the United States of America, residing at New Haven, county of New Haven and State of Connecticut, have invented a new, original, and ornamental Design for a Shoe Sole, of which the following is a specification, reference being had to the accompanying drawing, forming part thereof, wherein:

Figure 1 is a plan view of the sole; and
Figure 2 is a longitudinal section on the line
2—2 of Figure 1.

I claim:

The ornamental design for a shoe sole, as
shown.

WILLIAM F. CAIRNS.
